MOVABLE ELECTRIC RECEPTACLE

Wesley J. Kelley, Minneapolis, Minn.

Application March 9, 1934, Serial No. 714,819

7 Claims. (Cl. 247—3)

This invention relates to new and useful improvements in movable electric receptacles, and more particularly to a novel mounting for an electric receptacle adapted to be supported in a base board or other suitable support, whereby the receptacle may be conveniently moved from one place to another to accommodate electrical appliances, such as a radio or lamp, without the necessity of employing extension cords, which are often objectionable.

An object of the invention is to provide a movable electric receptacle comprising a suitable support having an elongated recess therein, open at one side to the atmosphere through a longitudinally extending slot in which the receptacle is slidably mounted, and means being provided for closing said slot, but permitting free movement of the receptacle therein.

A further object of the invention is to provide an elongated supporting member having one or more electric receptacles slidably mounted therein and adapted for independent movement, and a pair of electric conductors being mounted in said support and concealed therein in such a manner that they cannot be engaged by an instrument from the exterior of the support.

Other objects of the invention reside in the particular construction of the slot closing means; in the means provided in connection with the receptacle for operating or flexing the slot closing means to permit free traveling movement of the receptacle in said slot; and, in the general construction of the slot closing means, whereby the slot is maintained closed at all times, regardless of the position of the receptacle or the number of such receptacles supported in the slot, and also, whereby the receptacles are adapted for independent movement; and, in the specific construction of the slot closing means which comprises a pair of oppositely disposed flexible members provided at their adjacent edges with interlocking elements, which automatically operate to connect together said flexible members to thereby positively close the slot at opposite sides and between adjacent receptacles.

Other objects of the invention will appear from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may

be made within the scope of the claims which follow.

In the drawings:

Figure 1 is a side elevation showing the invention embodied in the construction of a base board, 5 showing two receptacles, and the means provided for closing the slot;

Figure 2 is a sectional detail view on the line 2—2 of Figure 3, showing the action of the slot closing means at each receptacle;

Figure 3 is an enlarged cross-sectional view on the line 3—3 of Figure 1;

Figure 4 is an enlarged detail sectional view on the line 4—4 of Figure 3, showing the means provided at opposite sides of the receptacle for actuating the slot closing means;

Figure 5 is a detail sectional view of the receptacle removed from the rest of the apparatus;

Figure 6 is a sectional view on the line 6—6 of Figure 7, showing another construction wherein the slot closing means consists of a pair of overlapping resilient elements;

Figure 7 is a cross-sectional view on the line 7—7 of Figure 6, showing the positions of the slot closing elements at the point where the extension of the receptacle extends through the slot;

Figure 8 is a longitudinal sectional view on the line 8—8 of Figure 9, showing another construction wherein the slot closing means consists of a pair of flexible spring actuated ribbons mounted 30 in suitable guides provided in the walls of the slot;

Figure 9 is a front view of Figure 8 showing a single receptacle mounted in the slot;

Figure 10 is an enlarged detail sectional view on the line 10—10 of Figure 9;

Figure 11 is a detail sectional view showing a simple manner of securing the slot closing ribbons to the body of the receptacle;

Figure 12 is a view showing still another construction wherein the slot in which the receptacle is mounted is open, and the electric conductors are concealed within the device so that they cannot be engaged from the open slot;

Figure 13 is a cross-sectional view of Figure 12 showing the device mounted in a base board;

Figure 14 is a detail sectional view of the receptacle removed from the guide slot;

Figure 15 is a bottom view of the receptacle; and

Figure 16 is a view showing the device provided with two receptacles adapted for independent movement.

In the selected embodiment of the invention here shown, for purposes of disclosure, there is

illustrated in Figures 1, 2, and 3, a supporting member 2 which may be in the form of a base board, door trim, or some other suitable fixed member, having an elongated recess 3 therein bounded at one side by a wall composed of longitudinally extending strips, generally indicated by the numerals 4, and each shown comprising wedge-shaped members 5 and 6. The adjacent edges of the members 5—6 of the strips 4 are spaced apart to provide a longitudinally extending slot 7, extending substantially the full length of the recess or chamber 3.

The receptacle, generally indicated by the numeral 8, is shown comprising a body portion 9 having a reduced extension 11, provided at its inner end with oppositely extending projections or flanges 12, spaced from the adjacent face 13 of the body 9. The reduced extension 11 is receivable in the slot 7, and the flanges 12—12 engage the inner faces of the members 5—6 of the strips 4, to thereby retain the receptacle in operative position in the slot 7.

The receptacle is here shown provided with a pair of spaced apertures 14 and 15 in which are mounted flexible contacts 16 and 17 provided with electrical conductor strips 18 and 19 which pass through the reduced extension 11 and terminate within the recess or chamber 3, in flexible contact elements 21 and 22. The contacts 21 and 22 electrically engage a pair of fixed conductors 23 and 24, respectively, shown secured to an insulating bar 25 suitably secured in the bottom of the recess or chamber 3 by such means as screws 26. It will thus be seen that the resilient contacts 16 and 17 of the receptacle 8 are constantly electrically engaged with the conductors 23 and 24. The conductors 23 and 24 are connected to a suitable source of electrical energy by such means as wires 27 and 28.

An important feature of this invention resides in the means provided for constantly maintaining the slot 7 closed, regardless of the position or positions of the receptacle or receptacles, as shown in Figure 1. In devices of this character, it is of utmost importance that the electric conductors 23 and 24 be so concealed and protected that persons cannot accidentally come in contact therewith.

To thus close the slot 7, there is shown in Figures 1, 2, 3, and 4, a pair of flexible elements 29 and 31, having portions clampingly secured between the wedge-shaped members 5 and 6 of the strips 4 by suitable screws 32. The adjacent edges of the flexible elements 29 and 31 overhang the walls of the slot 7, defined by the adjacent edges of the wedge-shaped members 5—6, and are shown provided with spaced link elements, generally indicated by the numerals 33 and 34, which are commonly known to the trade as "zippers."

Suitable devices 35 are shown secured to opposite sides of each receptacle 8 adapted to actuate the interlocking links 33 and 34 to move them into and out of interlocking engagement, as the receptacle is moved lengthwise in the slot 7. These actuating devices are of ordinary well-known construction such as commonly used in connection with zipper fasteners, and it is therefore thought unnecessary to herein illustrate and describe the same in detail.

By means of the flexible elements 29 and 31 and the zipper devices 33, 34, and 35, it will readily be understood that as the receptacle is moved from one position to another in the slot 7, one of the zipper devices 35 will actuate the elements 33 and 34, at one side of the receptacle, and thus

operatively connect them together, while the device 35 at the opposite side of the receptacle will cause the links 33 and 34 to become disconnected to thereby permit the reduced extension 11 of the receptacle to pass freely back and forth between the two flexible members 29 and 31, as best shown in Figure 2.

In Figures 6 and 7, there is illustrated another construction wherein the slot closing means consists of a pair of resilient ribbon-like members 10 36 and 37, preferably having their adjacent edges arranged in overlapping relation, as shown in Figure 6. The outer edges of the members 36 and 37 are secured to the supporting member or base board 38 by suitable clamping strips 39 and 41, 15 secured in rabbets 42 provided in the face of the supporting member 38 by such means as screws 43. The adjacent edges of the clamping strips 41 overhang the spaced walls of the chamber or recess 3, and are spaced apart to provide a longitudinally extending slot 44 in which the reduced portion 11 of the receptacle 8 may travel.

The slot closing elements 36 and 37 may be constructed of a suitable spring metal or other suitable resilient material, capable of flexing, as shown in Figures 6 and 7, to permit the reduced portion 11 of the receptacle to pass freely back and forth in the slot 44.

Figures 8, 9, 10, and 11 illustrate a construction wherein the slot closing means consists of a pair of flexible ribbon-like elements 45 and 46, each of a width sufficient to span a slot 51, and each having one end connected to the reduced portion 11 of the receptacle 8 by such means as rivets or pins 47. The opposite ends of the ribbon-like elements 45 and 46 are shown operatively engaged with spring-actuated rollers 48, suitably mounted at the ends of the elongated recess or chamber 3, as best shown in Figure 8.

The ribbon-like elements 45 and 46 have their edges received in suitable guides 49 provided in the adjacent edges of a pair of longitudinal strips or plates 52, secured in recesses 53 provided in the face of the supporting member 2, by such means as screws 54. The adjacent edges of the plates 52 cooperate to provide the walls of the slot 51.

In the form here shown, the movement of the receptacle 8 will, of course, be limited to the length of the flexible elements or ribbons 45 and 46. The receptacle, however, is freely movable back and forth in the slot 51 in the same manner shown in the previous figures, and may therefore be positioned at any point within the length of the slot.

In the construction shown in Figures 1 and 7, two or more receptacles may be mounted in the same slot, and each is adapted for movement independently of the other. In these figures, the slot closing elements do not move in a lengthwise direction in the slot, as does the flexible ribbon-like elements shown in Figure 8. The slot closing elements, shown in Figures 1 to 6 are separated by the reduced portion 11 of the receptacle, as shown in Figures 2 and 6, after which they resume their normal closed positions, as hereinbefore described.

Figures 12 to 16, inclusive, show another construction, comprising an elongated supporting member 58 recessed as shown at 56. A longitudinally extending rib 57 is shown provided between the recesses 56, upon which is suitably secured a strip or plate of insulating material 59, to the bottom face of which a pair of conductor bars 59 and 61 are suitably secured, as

shown in Figures 12 and 13. The insulating strip or plate 58 may be of bakelite and secured to the rib 57 by suitable means such as screws, indicated at 62 in Figure 13.

- 5 Similar insulating strips or plates 63 and 64 are suitably secured to the upper faces of the supporting member 55, and have their adjacent edges spaced apart to provide an elongated opening or slot 65 in which an electric receptacle 66 is slidably mounted. The slot 65 is disposed directly over the lower or inner plate 58 and the opposed edge portions of the latter extend into the recesses 56 beneath the edge portions of the plates 63 and 64, so that it is practically impossible for anyone to insert an instrumentality into the slot 65 in such a manner as to engage the electric conductors 59 and 61.

The receptacle 66 is shown in detail in Figures 14 and 15, and comprises suitable apertures 67 and 68 in which are mounted flexible contact clips 69 and 71, respectively. Flexible contacts 72 and 73 are electrically connected to the lower ends of the clips 67 and 68, and are preferably shaped as shown in Figure 13, whereby they extend around the opposed edges of the insulating plate 58 and have their terminals contacting with the conductor bars 59 and 61 with a yielding pressure. Thus, the contact clips 69 and 71 of the receptacle 66 are always in electrical connection with the circuit whereby the plug is always ready for use, regardless of where it may be positioned in the slot 65 of the supporting member 55.

The receptacle may be moulded of bakelite, and is shown provided at its bottom with an elongated portion 74 extending across the diameter of the plug and having oppositely disposed flanges 75 and 76 formed thereon, which cooperate with adjacent faces of the receptacle to provide opposed recesses or grooves 77 adapted to receive the adjacent edges of the insulating plates 63 and 64, as will readily be understood by reference to Figures 12 and 13. The width of the portion 74 is slightly less than the width of the slot 65 whereby the receptacle may readily be moved back and forth in said slot.

The device shown in Figure 12 is very compact and small in size, and may be fitted into a comparatively small groove or recess provided in the face of a base board, a door casing, a ceiling, or any other suitable place where it may be found desirable to provide electric outlets. In the form here shown, any number of receptacles may be mounted in the slot 65, and all of such receptacles are movable independently of one another whereby they may readily be positioned along the wall or ceiling to accommodate electric appliances or fixtures stationed about a room or shop.

60 The device is very simple and inexpensive and comprises comparatively few parts. The supporting member 55 may be formed of any suitable material such as bakelite or wood, and, in some instances, it may be desirable to form it of sheet metal, in which case, the conductor bars 59 and 61 must, of course, be well insulated therefrom. The device may be made to any suitable length and, if desired, may extend the full length of a room. The receptacles 66 are comparatively simple in construction, as is clearly shown in the drawings, and when fitted into the slot 65, as shown in Figure 12, may be moved freely back and forth therein and any strain exerted thereon will be taken up entirely by the opposed flanges 75 and 76, fitting against the

inner faces of the insulating plates 63 and 64. The receptacles are inserted into the slot 65 from one end of the device, as will readily be understood by reference to Figures 12 and 16.

The invention herein set forth, may readily be embodied in the construction of a base board or other suitable supporting member at small cost, and provides means whereby the receptacles may be freely moved about from place to place within the length of the slot in which they are supported, to thereby conveniently position them with respect to the electrical appliances to be served thereby. The slot closing elements positively close the slot so that access cannot be had to the chamber or recess 3 in which the electrical conductors 23 and 24 are mounted, thereby avoiding accidents from electric shocks, which might occur if the slots were open and the conductors 23 and 24 exposed.

I claim as my invention:

1. In a device of the class described, a member having an elongated recess therein open at one side, electric conductors in said recess, guides extending lengthwise of the recess, a receptacle mounted for traveling movement in said guides and having contacts engaging said conductors, and flexible, non-resilient means constantly closing the open side of said recess and permitting free movement of the receptacle therein.

2. In a device of the class described, a member having an elongated recess therein open at one side, electric conductors in said recess, a receptacle mounted for traveling movement in said recess and having contacts engaging said conductors, and means at opposite sides of said recess adapted for interlocking engagement to thereby close said recess and permitting free movement of the receptacle therein.

3. In a device of the class described, a member having an elongated recess therein open at one side, electric conductors in said recess, an electric receptacle mounted for traveling movement in said recess and electrically associated with said conductors, and zipper means for constantly closing the open side of said recess and permitting free movement of the receptacle therein.

4. In a device of the class described, a supporting member having an elongated recess therein, a wall of said recess having a longitudinally extending slot therein of less width than the width of said recess, a receptacle slidably mounted in said slot, means in said recess for supplying electric current to the receptacle, and non-resilient means closing the slot and permitting free movement of the receptacle therein.

5. In a device of the class described, a supporting member having an elongated recess therein, a wall of said recess having a longitudinally extending slot therein communicating with the recess, a receptacle slidably mounted in said slot, means in said recess for supplying electric current to the receptacle, and flexible elements overhanging said slot and normally interlockingly engaged to close the same, said flexible elements being operable by means on the receptacle to move them into and out of interlocking engagement, whereby the slot is constantly closed and the receptacle permitted free movement therein.

6. In a device of the class described, a supporting member having an elongated recess therein provided at one side with a wall having a longitudinally extending slot therein communicating with the recess, electric conductors in said recess connected to a source of electric energy, a re-

ceptacle slidably mounted in the slot in said wall and having contacts constantly engaging said conductors, zipper means at opposite sides of said slots for closing the same, and means on the receptacle for operating said zipper means and whereby the receptacle may be moved freely back and forth in said slot.

5. In a device of the class described, a support-

ing means having an elongated recess therein open at one side, electric conductors in said recess, an electric receptacle mounted for traveling movement lengthwise of the recess and electrical-
ly associated with said conductors, and interlock-
able means constantly closing the open side of
said recess.

5
WESLEY J. KELLEY.
